UNITED STATES PATENT OFFICE.

ROBERT M. LOCKWOOD, OF NEW YORK, N. Y., ASSIGNOR TO THE MOLECULAR TELEPHONE COMPANY, OF SAME PLACE.

RECEIVER FOR TELEPHONES.

SPECIFICATION forming part of Letters Patent No. 256,907, dated April 25, 1882.

Application filed September 10, 1881. (No model.)

To all whom it may concern:

Be it known that I, ROBERT M. LOCKWOOD, of the city, county, and State of New York, have invented new and useful Improvements in Receivers for Telephones, of which the following is a full, clear, and exact description, reference being had to the accompanying drawings, making part of this specification, in which—

10 Figure 1 is a side elevation of my improved receiver, partly in section, showing the arrangement of the diaphragm, &c.; and Fig. 2 is a plan or face view of the diaphragm.

My invention relates to an improvement in 15 diaphragms for telephone-receivers; and it consists in making such diaphragms of cork or equivalent non-resonant and non-magnetic material, provided with a central button of carbon or its equivalent, forming a hard, rasping, 20 and non-magnetic wear-plate for the reduced extension or recurved arm of the magnet to rest and act upon, as hereinafter explained.

The receiver in its organization or arrangement of parts may be similar to that described 25 in Letters Patent granted to Lockwood and Bartlett June 15, 1880, No. 228,855; or it may be made in any usual or preferred form, so long as the magnet employed therein is provided with a yielding or reduced extension resting in 30 contact with the diaphragm.

The body of the diaphragm (indicated at A) is made of cork or some equivalent non-resonant or non-magnetic material, and by preference is made in the form of a central disk, A, 35 with a ring, A', of similar material, surrounding it, and secured in place by means of thin elastic overlapping rings in a manner described in another application of even date herewith.

40 The diaphragm has a central perforation formed in it, in which is secured a small disk or button, B, of carbon or some equivalent non-magnetic material—such, for instance, as pumice—having a gritty or rasping substance or na-

ture, and with the surface of which the yielding or reduced extension of the magnet may rest in contact, and which will serve to impart the disturbances in the magnet or in the line wire or circuit to the molecules of the cork, through which they are conveyed by molecular action or disturbance.

The button or disk B may be secured in the cork in any suitable manner so long as it is brought into actual contact therewith, and for this reason I prefer to apply it in the central 55 perforation in the latter when the cork has been softened and rendered yielding by steaming or otherwise, when the button can be forced into place, and the cork being afterward dried under pressure, the carbon button 60 will be firmly and securely held in place therein without the aid of glue, cement, or other fastening which would separate it from the cork. By this arrangement of central button or disk a hard non-magnetic conductor and 65 wear-plate is interposed between the yielding extension of the magnet and the cork, and disturbances in the current or in degree of polarity in the magnet may be imparted to the cork with greatly-increased intensity, adapt- 70 ing them to be much more easily and distinctly recognized by the ear.

Having now described my invention, what I claim as new, and desire to secure by Letters Patent, is—

75 In a telephone-receiver, a diaphragm of cork, provided with a central button of carbon or its equivalent, applied thereto substantially as specified, in combination with the magnet having the reduced elastic extension resting in contact with said button, substantially as and for the purpose described.

In testimony whereof I have hereunto set my hand this 9th day of September, A. D. 1881.

ROBT. M. LOCKWOOD.
